UNITED STATES PATENT OFFICE.

PAUL HENZE, OF KAMSACK, SASKATCHEWAN, CANADA.

BROOM-HOLDER.

1,089,702.

Specification of Letters Patent.

Patented Mar. 10, 1914.

Application filed February 19, 1913. Serial No. 749,394.

To all whom it may concern:

Be it known that I, PAUL HENZE, of the village of Kamsack, in the Province of Saskatchewan, Canada, have invented certain new and useful Improvements in Broom-Holders, of which the following is the specification.

The invention relates to a broom holder and the object of the invention is to provide an inexpensive simply constructed device of this class in which a broom can be placed and locked thereby preventing the broom from being stolen or taken away.

With the above object in view the invention consists essentially in a back plate provided with a pair of connected side wings and a pair of lugs, a spring hasp carried by the lugs and provided with a slot and cross opening and a lock for securing the hasp to the arms, the parts being arranged and constructed as hereinafter more particularly described.

Figure 1 represents a perspective view of my device showing it as it appears when in use. Fig. 2 is a side view of the same.

In the drawing like characters of reference indicate corresponding parts in each figure.

1 represents a back plate supplied with a pair of opposing side wings 2 and 3 having their ends brought together centrally and fastened by a rivet 4, the extremities of the wings being supplied with registering openings 5 for a purpose later explained. The back plate is also supplied with an opposing pair of similar lugs 6 and 7 located above the wings and has also a number of vertically alined and centrally located openings 8 therein, for the reception of screws 9 which screws fasten the plate permanently to a wall or such like structure.

10 is a spring hasp having the upper end thereof pivotally secured to the lugs by a cross bolt 11 and the lower end thereof supplied with a slot 12 arranged when the hasp is thrown down to receive the extremities of the wings. A circular opening 13 is formed in the body of the hasp centrally which opening is in diameter slightly larger than the diameter of the usual broom handle.

14 is a padlock having the locking rod 15 thereof adapted to pass through the openings 5 in the wings.

55 When the device is to be used the padlock is undone and the hasp is swung from the

wings. The handle 16 of the broom 17 is then passed into and through the opening 13 and the hasp is then pressed down over the extremities of the wings and the locking rod 15 of the padlock is inserted in the openings 5 and locked. It is here pointed out that as the hasp is swung down it jams against and bites into the opposite sides of the broom handle, this effecting in reality the locking of the broom in the holder. One can easily slide the broom handle upwardly but of course owing to the broom it cannot be removed from the holder in this way. If one attempt to pull the handle down it will not move as the edges of the hasp at the sides of the opening 13 simply bite harder into the sides of the handle.

It will be noted that when in the holder the broom handle passes directly across the screws 9 so that one would have considerable difficulty in removing even the screws if they attempted to steal both the holder and the broom.

What I claim as my invention is:

1. A broom holder comprising a suitably supported back plate provided with a pair of extending and connected side wings, a hasp pivotally secured to the back plate and having a centrally disposed opening therein adapted to receive the handle of a broom and means for locking the hasp to the wings, as and for the purpose specified.

2. A broom holder comprising a suitably supported back plate having a pair of opposing similar forwardly turned and connected side wings, a hasp pivotally secured to the back plate at a point above the wings, said hasp being provided with a centrally disposed opening adapted to receive the handle of a broom and releasable means for securing the hasp to the forward extremities of the side wings, as and for the purpose specified.

3. A broom holder comprising a back plate provided with a pair of opposing similar side wings bent forwardly to the front of the plate and connected one to the other there being registering openings formed in the extremities of the wings, a spring hasp pivotally secured to the body of the plate at a point above the wings, said hasp being provided with a centrally disposed opening adapted to receive the handle of a broom and having further a slot formed in one end thereof adapted to receive the extremities of the wings and releasable locking

means insertible within the registering openings of the wings, as and for the purpose specified.

4. A broom holder comprising a suitably supported back plate having a pair of similar opposing side wings extending forwardly therefrom and riveted together in advance of the plate, the extremities of the wings being supplied with registering openings, opposing lugs located above the wings and extending from the plate, a spring hasp pivotally secured to the lugs and having a

centrally disposed opening therein adapted to receive the handle of a broom and provided further at one end with a slot adapted to receive the extremities of the wings and a padlock for securing the hasp to the wings, as and for the purpose specified. 15

Signed at Kamsack this 23rd day of September 1912.

PAUL HENZE.
